LOCKING DEVICE FOR REVOLVING
MEMBERS

Herbert C. Reaux, Toledo, Ohio

Application July 21, 1933, Serial No. 681,615

3 Claims. (Cl. 70—50)

My invention relates to locking devices for rotative members in various predetermined positions. The invention particularly relates to a device having means movable with a rotative member and adapted to be engaged by a fixed member supported in an adjoining fixed part, such as the supporting frame of the rotative member.

The invention particularly lends itself to use in connection with closures, such as a revolving door, and provides a means for effectively locking or unlocking a revolving door.

The invention has for an object to provide a revolving door lock having means carried by the door shaft adapted to be engaged by an element supported in the door frame to lock the revolving door as against further movement relative to the frame. Another object of the invention is to provide a revolving door lock having a controlling means that may be operated at a remote point from the door. A further object of the invention is to provide a revolving door lock designed to arrest the further movement of the door when the wings of the revolving door are located at substantially a 45° angle to a horizontally extending line describing the center of the passageway in which the door is located. In this connection the invention provides a door lock which, when applied to revolving doors, permits the trapping of undesirable intruders and pilferers between the door casement and the wings and provides a revolving door lock for buildings in which banks or depositories of wealth are kept. A particular object of the invention is to provide a toothed member operable on, and movable with, the supporting shaft of the revolving door, a latch bolt slidably supported in a frame and adapted to engage the toothed member to prevent further movement of the toothed member and the door, and electrical means for operating said latch bolt.

A still further particular object is to provide a revolving door lock having means supported on the door for automatically establishing a locked condition upon operation of the door through a predetermined angular movement. A still further object is to provide a revolving door lock of relatively low cost and high efficiency.

The invention consists of other features and advantages which will appear from the following descriptions and upon examination of the drawing. Structures containing the invention may partake of different forms and may be varied in their details and still embody the invention. To illustrate a practical application of the invention,

I have selected a locking device for a revolving door embodying the invention as an example of the various structures and details thereof that contain the invention and shall describe the selected structure hereinafter, it being understood that variations may be made without departing from the spirit of the invention. The particular structure selected is shown in the accompanying drawing.

Fig. 1 of the drawing illustrates a perspective view of the lock chosen for purposes of illustration. Fig. 2 illustrates a plan view of the lock shown in Fig. 1. Fig. 3 illustrates an end view of the circuit breaker used on the door lock chosen. Fig. 4 illustrates diagrammatically a top view of a revolving door and showing it in a locked position. Fig. 5 illustrates diagrammatically the electrical circuit which controls the operation of the door lock.

Heretofore, revolving door locks consisted of a key operated bolt which engages a face plate located in the door panel or suitable sliding floor or ceiling bolts. A revolving door lock partaking of the features of my invention has a frame supported, preferably, above the head panel of the door casement and hidden from general view. The frame supports a discular member that is keyed to the door supporting shaft. The discular member has peripheral teeth or recesses which are adapted to be engaged by a latch bolt element. The bolt element is slidably supported in the frame and biased toward a position of engagement with the discular member and its teeth. The bolt element is held in an unlocked position by means of a magnetically operated dog that engages the bolt and holds it against the bias. The bolt is withdrawn from a locked position by means of an electromagnet and thus the locking and unlocking of the revolving door may be accomplished at a remote point by means of a switch which completes an electrical circuit through the coils of the electromagnets as desired.

In the construction shown in the drawing, a revolving door 1, having wing portions 9, is supported on a shaft 2 to which it is keyed, as shown at 3. The shaft 2 extends through a head panel 4 of the door casement and has a bearing member 5 supported on a frame 6. The frame 6 has leg portions 7 that are connected to the head panel 4, as by the bolt, washer and nut assemblies 8.

In order to restrict the rotation of the door 1 to but one direction, a toothed wheel or ratchet 10 is keyed to the shaft 2 and is adapted to be

slidably engaged by the finger of a suitably biased pawl 11. The pawl 11 is pivotally supported, as at 12, on the frame 6 and is adapted to engage the ratchet 10 when the ratchet and the door 5 are moved towards the pawl. If desired, the teeth 13 of the ratchet 10 may have cushion insets 14 affixed, as by the bolts 15, to the leading faces of the teeth 13 and thus eliminates much of the noise incidental to rotating the ratchet 10 in 10 contact with the pawl 11 during angular movements of the door. Thus, the door 1 may only be revolved about its axis and on the shaft 2 in a direction leading away from the pawl 11.

Surmounting the ratchet 10 and keyed to the 15 shaft 2 is a locking member 15. The member 15, preferably discular in shape, is adapted to rotate in a recess 16 formed in the frame 6 upon movement of the door 1. The member 15 has teeth 18 which are adapted to be engaged by 20 a latch bolt 17. The latch bolt 17 is slidably supported in a way 22 formed in the frame 6 and is biased toward the member 15 by a suitable compression spring 19. The bolt 17 has a shoulder portion 20 that is engaged by a dog 21 25 when the bolt is in an open position relative to the member 15. The dog 21 holds the latch against the pressure of the spring 19 in an open position and when withdrawn from engagement with the shoulder portion 20, permits the bolt 30 to move toward and engage one of the teeth 16 of the member 15, thus locking the door 1.

The dog 21 is operated to engage and disengage the shoulder portion 20 by a plunger 25 connected to a movable magnetic armature 26. 35 The plunger 25 is supported for reciprocal movement in the frame 6 and is provided with a compression spring 27 which yieldingly resists movement of the plunger outwardly with respect to the frame 6. The armature 26 is located in an 40 operable position with respect to an electromagnet 28. The electromagnet 28 has the usual related core 29 and coil 30. The coil 30 is connected to suitable source of electrical energy through a line 31, master switch 32, contacts 45 33, line 34, condenser 35, contact 36, circuit breaker 37, contact 38, line 39, coil 30, line 40, switch 41, and return line 42.

Thus, as illustrated diagrammatically in Fig. 5, when the switch 41 is closed, the coil 30 will 50 be energized and the armature 26 drawn toward the electromagnet 28 against the tension of the spring 26 to disengage the dog 21 from the shoulder portion 20, permitting the bolt 17 to slide into engagement with the member 15 and engage 55 one of the teeth 18, thus locking the door 1 against further movement.

In order that the circuit above described may be broken upon release of the latch bolt 17 by the dog 21 so as to re-establish the tumbler in 60 position for unlocking, the circuit breaker 37 is provided in circuit and operates automatically upon release of the bolt 17 to open the coil circuit and permit the compressed spring 27 to move the plunger 25 and the dog 21 in a position to 65 subsequently engage the shoulder 20 upon withdrawal of the latch bolt from engagement with the teeth 18. The particular breaker 37 provided comprises a pair of terminals 45 and 46 formed of a suitable electro-conductive material 70 supported on the frame 6 and insulated therefrom by an insulating block 47. The terminal 45 supports the fixed contact 36 that is adapted to be engaged by the movable contact 38 slidably supported in the other terminal 46. The movable contact 38 has a shank portion 48 which ex-

tends through an opening formed in the terminal 46 and slidably fits an insulated bracket 49 affixed as by the bolts 50 to the armature 26. The shank 48 may be provided with limiting stops 51 and 52. A spring 53 is located on the shank 48 so as to bear against the stop 51 and the bracket 49 and operates to move the shank 48 and the contact 38 toward the fixed contact 36 to maintain the circuit closed upon release of the armature 26 from the influence of the magnet 28. The stop 52 is adapted to be engaged by the bracket 49 as the armature is moved toward the magnet 28. Thus, upon closure of the switch 41, the coil 30 is energized and the armature 26 drawn toward the electromagnet 28 against the tension of the spring 27 to withdraw the dog 21 from engagement with the shoulder 20. As the armature 26 approaches contact with the core 29, the bracket 49 engages the stop 52 to draw the contact 38 from contact with the fixed contact 36 breaking the circuit of the coil 30 upon the contact of the armature with the core. The circuit of the coil 30 being open, the compressed spring 27 exerts its influence to move the armature 26 together with the bracket 49 away from the core 29 and 90 locates the dog 21 in a yieldingly pressing position against the side of the bolt and in a position for ready engagement of the shoulder 20 upon retraction of the bolt. As the armature is moved away from the core 29, the bracket 49 causes 95 compression of the spring 53 which exerts itself on the stop 51 on the shank portion 48 and operates to move the contact 38 with increasing force towards and against the contact 36, insuring thereby a closure of the circuit through the 100 breaker and its contacts.

If desired, a switch 55, operable by the door 1 or its wings 9, may be provided and be connected in parallel circuit with the circuit of the breaker 37. The switch 55 has an operating shoe 56 that 115 is pivotally supported, as at 57, to a bracket 58. The bracket 58 is supported on the frame 6. The shoe 56 is adapted to slidably engage the upper edges of the wings 9 of the door 1 and to be moved angularly about its pivot 57 as each wing 9 of 120 the door 1 passes under the shoe. The shoe 56 is connected to the switch 55 and operates to close the switch upon passage of the door wings under the shoe 56. The switch is connected by the line 60 to the contact 36 and by the line 61 125 to the line 39. Thus should the contacts 36 and 38 fail to close, a circuit may be completed through the contact 36, line 60, switch 55, line 61 and line 39 to energize the coil 30 for withdrawing the dog 21, as described, and effecting 130 locking of the door.

In order to unlock the door 1, the latch bolt 17 must be withdrawn from engagement with the teeth 18 of the member 15. The latch bolt 17 is connected by a suitable stem 65 to a movable armature 66. The stem 65 is supported for reciprocal movement in the frame 6 and locates the armature 66 in operative relation with an electromagnet 68. The electromagnet 68 has a coil 69 and core 70. Thus, upon energization of the coil 69, the core 70 will exert a magnetic influence on the armature 66 to move the stem 65 and latch bolt 17 out of engagement with the teeth and to a position where the shoulder 20 of the bolt may be engaged by the dog 21, thereby 140 unlocking the door 1.

The coil 69 is energized from a suitable source by the line 31, switch 32, contact 72, line 73, coil 69, line 74, contact 75, switch 32, and return. Thus, upon closure of the switch 32 with con- 150

tacts 72 and 75, the bolt 17 will be withdrawn from locked position. If desired, a spring 78 may be located on the stem 65 of the latch bolt and undergoes compression during the withdrawal of the latch bolt and operates to move the latch bolt to locked position upon disengagement of the dog 21 with the latch bolt.

If desired, the facing portions of the cores 70 and 29 may be provided with cushion elements 10 80 which serve to eliminate the noise of contact between the cores and their respective armatures 66 and 26.

In operation, the door 1 is located in a passageway 81. The passageway 81 has arcuate casement walls 82 of a radius substantially that of the width of a wing 9. Assuming the door 1 to be open or free to revolve and it is desired to lock the door, the switch 41 is thrown, either manually or through an automatic alarm device, the dog 20 21 will be withdrawn from engagement with the bolt 17, and the door will be free to revolve to a position, as indicated in Fig. 4, forming a confining chamber 85 between the wings 9 and the casement 82 in which an individual, attempting 25 to pass through the passageway, may be trapped and prevented from escaping. It will be appreciated that in the normal use of the door by ordinary traffic, the door will not be left in a position whereby locking thereof will be effected immediately with the operation of the switch. Consequently, a certain amount of free angular movement of the door will be permitted to allow the establishment of the trap as described. The opening of the door may be accomplished by 30 35 throwing the switch 32 as described.

I claim:

1. A lock for a revolving door supported on and keyed to a shaft, a lock supporting frame having a recess and adapted to rotatably support the shaft, a discular member having a plurality of teeth disposed in said recess and adapted to be keyed to the shaft, the frame having a way communicating with the recess, a latch bolt slidably supported in said way and normally urged 40 45 toward engagement with said teeth, magnetic means supported on the frame for retracting the latch bolt from said engagement, means for energizing said magnetic means, a second way formed in the frame communicating with the first named way, an element slidably supported in the said second way and urged toward said first named way whereby the latch bolt when in retracted position may be engaged by said element, a second magnetic means supported on the 50 55 frame for retracting the tumbler element, and

means for energizing said second magnetic means including an element actuated upon rotation of the door.

2. A lock for a revolving door supported on and keyed to a shaft, a frame, the shaft journaled in the frame, a recess formed in the frame concentric with the said shaft, a disc having a plurality of teeth adapted to be keyed to the said shaft and disposed in said recess, a way formed in said frame and extending from one edge thereof to and communicating with said recess, a latch bolt slidably supported in said way and normally urged toward the said recess whereby the disc teeth will be engaged by the said latch bolt, magnetic means supported on the frame proximate to the way for moving the said latch bolt away from said recess, a controllable means for energizing said magnetic means, a second way extending at substantially right angles to the first named way and communicating therewith, an element slidably supported in said second way and normally urged to engage the said latch bolt, magnetic means supported on the frame adapted to move the element away from the latch bolt, and means for energizing said magnetic means including a trip element actuated by the door upon movement thereof.

3. A lock for a revolving door supported on and keyed to a shaft, a frame adapted to be supported in transverse relation to the axis of the shaft and having bearing portions for said shaft, the frame having a recess and a way extending from the recess to one edge of the frame, a disc keyed to the shaft and having a plurality of peripheral teeth, the disc disposed in the recess, a latch bolt slidably supported in said way, resilient means disposed within said way tending to move said latch bolt toward said recess whereby the disc may be engaged by said latch bolt, a magnetic means supported on the edge of the frame in proximity to the way for moving the latch bolt in opposition to said resilient means, means for energizing said magnetic means, a second way extending from a frame edge to and communicating with the first named way, a dog element slidably supported in said second way, resilient means disposed in said second way tending to move the dog element toward an engaging position with said latch bolt, a second magnetic means for moving the dog element in opposition to the second named resilient means, and means for energizing said second magnetic means including a shoe pivotally supported on said frame and actuated by the movement of the revolving door.
